US0D1083689S

(12) **United States Design Patent** (10) **Patent No.:** **US D1,083,689 S**
(45) **Date of Patent:** **** Jul. 15, 2025**

(54) **BICYCLE TIRE LEVER**

(71) Applicant: **Jesus R. Enriquez**, Tucson, AZ (US)

(72) Inventor: **Jesus R. Enriquez**, Tucson, AZ (US)

(**) Term: **15 Years**

(21) Appl. No.: **29/912,079**

(22) Filed: **Sep. 13, 2023**

Related U.S. Application Data

(63) Continuation-in-part of application No. 29/807,705, filed on Sep. 14, 2021, now Pat. No. Des. 1,028,803.

(57) **CLAIM**

The ornamental design for a bicycle tire lever as shown and described.

DESCRIPTION

FIG. 1 is a front perspective view of a bicycle tire lever showing my new design;

FIG. 2 is a back perspective view thereof;

FIG. 3 is a front view thereof;

FIG. 4 is a back view thereof;

FIG. 5 is a side view thereof; the opposite side view being a mirror image thereof;

FIG. 6 is a top view thereof;

FIG. 7 is a bottom view thereof; and,

FIG. 8 is a side view thereof shown in a condition of use. In FIG. 7, the broken lines depict portions of the bicycle tire lever that form no part of the claimed design.

In FIG. 8, the broken lines illustrate environmental subject matter that form no part of the claimed design.

1 Claim, 7 Drawing Sheets
